CLAIM

The ornamental design for a double corner trowel, as shown and described.

DESCRIPTION

FIG. 1 is a top, front, left perspective view of a double corner trowel showing my new design;

FIG. 2 is a bottom, rear, right perspective view thereof;

FIG. 3 is a top plan view thereof;

FIG. 4 is a bottom plan view thereof;

FIG. 5 is a rear elevation view thereof;

FIG. 6 is a front elevation view thereof;

FIG. 7 is a right side elevation view thereof; and,

FIG. 8 is a left side elevation view thereof.

The broken lines depict aspects of the double corner trowel in which the design is embodied that form no part of the claimed design.

1 Claim, 3 Drawing Sheets
